HATCH PLUG FOR CLOSING OPENINGS
IN ICE CONTAINERS OF REFRIGERATOR CARSEdwin R. Battley and George E. McCoy,
Montreal, Quebec, Canada

Application January 26, 1945, Serial No. 574,790

4 Claims. (Cl. 62—17)

1

This invention relates to railroad refrigerator cars having hatches in the roof thereof through which refrigerant containers, positioned immediately below the roof, but spaced slightly therefrom for air circulation therebetween, are serviced, said containers having openings in the top surface thereof registering with the hatch openings in the car roof, and is an improvement over the construction shown in Bonsall Patent No. 2,136,999 of November 15, 1938.

The invention more specifically relates to such cars having refrigerant containers of the solid type for holding brine or water ice as the refrigerating medium, and which containers, therefore, must have means to prevent service movements of the car from causing the liquid in said containers to surge out through the filling opening into said space thereabove and thence into the car.

It is the principal object of our invention to provide a conveniently operable means for closing the filling opening in the container.

It is a further object of the invention to associate said closing means with the hatch plug of the car so that when said plug closes the hatch it also closes the opening in the refrigerant container.

A still further object of the invention is to so associate the container with the roof and hatch plug so that when the plug is opened for ventilation air coming into the car through the hatch may circulate about the container and enter the lading compartment of the car.

Still another object of the invention is to provide means between the refrigerant container and the car roof so as to materially retard, if not prevent, surging of the liquid therein out through the filling opening.

Other objects and advantages of the invention will appear in the following description thereof.

Referring now to the accompanying drawings forming part of this application and wherein like reference characters indicate like parts:

Figure 1 is a vertical sectional view of one of the hatchway constructions showing the relation of the refrigerant container thereto.

Figure 2 is a view similar to Figure 1 showing the preferred form of closing the filling opening in the refrigerant container.

Figure 3 is a view similar to Figure 2 showing a modified form of closing the filling opening in said container.

Figure 4 is a cross sectional view showing a further modified form of the invention.

2

Figure 5 is a vertical sectional view showing a still further modification of the invention.

Figure 6 is a section on line 6—6 of Figure 5.

In the drawings, 1 represents the side wall of a refrigerator car, and 2 the roof thereof, both of which, it will be understood, are of suitable insulated construction, the details of which may be omitted, since they form no part of our present invention.

10 A hatch opening 3 is formed in the roof 2, extending therethrough and is provided with a hatch frame as is common. Immediately below the roof, but spaced slightly therefrom, is a refrigerant container 4, having an opening 5 in the upper surface thereof which registers with the hatch opening 3. The container 4 is spaced from the roof 2 to provide an air circulating and air cooling space 16, and also to provide a path for ventilating air to the interior of the car when the hatch plug is removed or raised for ventilating purposes. The container 4 is formed with an inwardly turned flange 6 about the perimeter of the opening 5, and in Figures 1 and 2, these flanges are turned backwardly toward the sides of the container, which flanges, in addition to strengthening the top of the container around the opening, provide means to at least retard, if not prevent, the surging of the liquid 15 within the tank, due to service movements of the car, from escaping therefrom through said opening 5, into the space 16 and thence possibly into the interior of the car.

As is common in refrigerator cars of this type, a substantially horizontally disposed drip pan (or ceiling) 1 is installed below the refrigerant container 4 and spaced slightly therefrom to form an air cooling space 17 therebetween. This drip pan extends from approximately the longitudinal center of the car 19 where it is provided with an upwardly extending baffle 8 to a flue 9 associated with said wall 1. A path for circulating air, when the car is under refrigeration, is thus provided under the container to and downwardly through 40 said flues, as indicated by the arrows in Figures 1 and 2.

The hatch plug is shown at 10, the major portion of which may be of a construction as is found in such plugs now on the market. These plugs 50 may comprise an integral cover plate or lid 11, as shown in Figure 3, which overlaps the perimeter of the hatch frame and is provided with any acceptable type of weather-sealing material 12 therebetween to seal the opening against entrance 55 of cinders or other foreign matter therethrough,

or the lid 19 may separate from the plug, as shown in Figures 1, 2 and 4.

In Figures 2 and 3 the body of the plug is shown as extended in thickness or depth so that when in position to close the hatchway it will extend to and contact the perimeter of the filling opening 5 in the container.

In Figure 2 this contact is illustrated as made by the bottom of the plug body 20 resting upon the edge of said opening, and sealing material 13 may be provided to seal the opening when the plug is resting thereupon. The flanges 6 also stiffen the perimeter of the opening 5 against deformation and thus assure a seal.

In Figure 3 the flanges 21 about the opening 5 extend inwardly substantially parallel with the plane of the sides of the plug body and the lowermost portion of the plug body 22 is shown as extending slightly within said filling opening 5, and the sealing means 14 may be provided between the side walls of the plug and flange 21 to seal said opening when the plug is installed therein.

In Figure 4 we have shown a modified form of the invention wherein a baffle construction is provided about the perimeter of the opening 5 and in the space 16 between the container 4 and the roof 2. This baffle construction comprises a series of overlapping vanes 25-26 so that air may readily circulate therethrough, but any surging of liquid within the tank is effectively retarded, if not prevented, from escaping into the space 16. Should any surging liquid escape over some of the vanes, we have provided small drain holes 27-28 through the upper wall of the tank so that said liquid may drain back thereinto. Figure 4 shows the plug removed and the cover slightly raised for ventilation, and the arrows indicate the movement of the ventilating air.

Figures 5 and 6 show the refrigerant containers being formed of separable parts. To form the flanges shown in Figures 1, 2 and 3 in the top of the containers may be difficult and, therefore, there is shown, in Figures 5 and 6, the flanges as being of separate material and then welded to the tops of the containers. The top itself is made separate from the remainder of the container and the downwardly and outwardly inclined collar 30 welded or otherwise secured to an upstanding flange 31 about the perimeter of the filling opening 32. The hatch frame 33 projects downwardly into the collar so that the lower margin of said hatch frame and collar 30 cooperate to retard splashing of liquid in the container into the space 16 between the container and the roof.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

We claim:

1. In a refrigerator car having a hatch opening with tapering sides in the roof thereof, a refrigerant container spaced below said roof so as to provide a space between said roof and said container which communicates with the hatch open-

ing and the interior of the car for ventilating purposes, said container having a filling opening therein registering with said hatch opening, and a removable hatch plug having portions engageable with the walls of the hatch opening to close the hatch opening to retard heat infiltration and other portions engageable with the container to simultaneously close the filling opening to retard the escape of refrigerant from the container.

2. In a refrigerator car having a hatch opening with tapering sides in the roof thereof, a refrigerant container spaced below said roof so as to provide a space between said roof and said container which communicates with the hatch opening and the interior of the car for ventilating purposes, said container having a filling opening therein registering with said hatch opening, said container provided with a stiffening flange around the perimeter of the filling opening, and a removable hatch plug having portions engageable with the walls of the hatch opening to close the hatch opening to retard heat infiltration and other portions engageable with said flanges of the container to simultaneously close the filling opening to retard the escape of refrigerant from the container.

3. In a refrigerator car having a hatch opening in the roof thereof, said opening having parts at an angle to the plane of the roof, a refrigerant container spaced below said roof so as to provide a space between said roof and said container which communicates with the hatch opening and the interior of the car for ventilating purposes, said container having a filling opening therein registering with said hatch opening, said container provided with a continuous surface around the perimeter of the filling opening substantially normal to the plane of the top of the container, and a removable hatch plug having portions engageable with said parts to close the hatch opening and other portions engageable with said surface to simultaneously close the filling opening to retard the escape of refrigerant from the container.

4. In a refrigerator car having a hatch opening in the roof thereof, a refrigerant container spaced below said roof so as to provide a space between said roof and said container which communicates with the hatch opening and the interior of the car for ventilating purposes, said container having a filling opening therein registering with said hatch opening, and a removable hatch plug adapted to simultaneously close said hatch opening and said filling opening when in closed position.

EDWIN R. BATTLEY.
